ABSTRACT OF THE DISCLOSURE

Determination of thyroid hormone uptake from blood serum by a secondary binding substance or absorbent is executed by flowing a serum sample through a column containing the absorbent in a very brief period. A residence time of three minutes or less is typical when using a cross-linked strong base anion exchange resin as the absorbent.

This invention relates to the clinical determination of thyroid function. More particularly, it relates to the determination of thyroid hormone uptake by a secondary binding substance or absorbent from which an estimation of the concentration of available thyroid protein hormone binding sites in blood can be made.

Briefly, the invention involves disposing a competitive binding absorbent for thyroid hormone in a column. A fluid sample containing thyroid hormone bound by thyroid hormone binding proteins is flowed through the column. The column dimensions and absorbent are selected to competitively bind and retain about 10-90 weight percent of the bound thyroid hormone in the fluid sample during a single passage of the sample through the column. The amount of thyroid hormone retained in the column relative to the thyroid hormone present in the column effluent is then measured.

By way of background, it is known that thyroxine (T-4) and tri-iodothyronine (T-3) in plasma are bound by dissociable linkages to specific serum proteins collectively referred to as thyroid hormone binding proteins. The degree of saturation of the serum proteins by thyroid hormone varies in different states of thyroid function. In hyperthyroidism, for example, the serum proteins are saturated with thyroid hormones to greater extent and therefore the number of available binding sites on serum proteins (unsaturated thyroid-hormone-binding capacity) is decreased. The converse is true in hypothyroidism. Since thyroxine is bound to serum proteins more firmly than tri-iodothyronine, the number of available binding sites on serum proteins depends mainly on the concentration of thyroxine in plasma.

Hamolski et al., *J. Clin. Endocr.* 17, 33 (1957) described the uptake of I-131 labeled tri-iodothyronine by red cells in whole blood as a method for estimating the saturation of thyroid binding proteins. They discovered that I-131 labeled tri-iodothyronine incubated with plasma from hyperthyroid patients demonstrated a lower rate of absorbence of radioactivity onto the erythrocytes as compared with euthyroid patients. This method has proved valuable in the assessment of thyroid diseases, abnormalities of thyroxine transporting protein, and in the evaluation of thyroid therapy. Since the measurement is performed using a radioactive labeled hormone, interferences from serum organic iodine contaminants is minimized.

In general, these T-3 uptake tests are performed by equilibrating trace amounts of radioactively labeled T-3 with a sample of patient's serum. This combination is then equilibrated with a secondary binding material such as red blood cells. The secondary absorbent has a certain affinity for the T-3 so that some of the T-3 will be ab-

2

sorbed by this secondary binding material. If the absorbent has a fixed affinity for T-3, the distribution of the radioactive T-3 between the absorbent and the serum proteins will depend upon the number of available binding sites on the serum proteins.

Due to various inherent difficulties in using red blood cells, a variety of other absorbents have been utilized. One such absorbent is a strong base anion ion exchanger which has been utilized in the form of free resin beads, resin 10 imbedded in a sponge, and as a membrane. Another material that has been used is hemoglobin absorbed on charcoal. Such materials have the ability to remove T-3 from the binding proteins.

In all of the prior competitive binding procedures the 15 absorbent and the serum sample have been contacted on a batch basis as distinguished from the column technique of this invention. In these prior procedures an equilibrium condition or a condition approaching equilibrium has been sought because it has been felt that clinically reproducible

20 results could only be achieved in that way. To this end the serum sample and the absorbent were constantly mixed and moved as by shaking or turning for a relatively extended period of time varying from about 30 minutes to about an hour and a half. At the end of the mixing 25 period a separation of the absorbent and the liquid phase was necessary in order to determine the percentage of uptake by the absorbent. Care was needed to obtain uniformity in the mixing time with the samples being tested and the controls used to obtain useful known values for 30 the test procedure.

In accordance with the present procedure, these disadvantageous steps and long time periods are eliminated. In general, the new column procedure provides for a 35 residence time of contact between the sample and the absorbent of not more than about 10 minutes and most commonly not more than about 5 minutes. In the preferred embodiment to be described hereinafter the residence time is less than about three minutes. At the conclusion of the residence period the liquid phase is 40 directly obtained as column effluent separated from the solid phase absorbent so that there is no need for a separation step as in the previously used batch technique. Despite the fact that the residence time is relatively very brief, comparable or better results than that obtained with prior 45 techniques are achieved. This is most surprising when considering the efforts previously put forth in terms of continuous mixing for extended periods of time in order to obtain or approach a batch equilibrium condition.

In the present column technique no equilibrium condition 50 between absorbent and solution exists. Instead a constantly changing relationship between absorbent and solution is presented as the solution moves through the column absorbent. In a sense the results from the present technique are generated by a series of initial uptakes of 55 thyroid hormone by successive portions of absorbent as the solution moves through the column. At the point of each initial uptake the slope of an uptake curve which can be drawn is so rapidly changing that an acceptable degree of reproducibility of results would not be expected. 60 Nevertheless, it has been found that the present column technique provides results comparable or better than the batch technique. For example, 17 portions of the same sample of serum have been processed in a column in accordance with the present method and the percent error 65 was 2.5%. This percent error is better than most prior art methods and quite acceptable for clinical diagnostic purposes. In addition, the present method has been compared with the prior art method using a batch equilibrium procedure and a straight line correlation between the two 70 methods was obtained. In only 2% of the cases tested was a result obtained by the present method which differed from that of the prior batch technique.

Apart from its simplicity and time savings, another feature believed to be offered by the present method is that it provides a measurement related to the rate of dissociation of T-3 from its protein binding sites. In the prior batch procedures conditions have been adjusted so that an equilibrium condition or one approaching equilibrium was obtained. Such test results provide only a measurement of the equilibrium binding capacity of the binding sites. In the present method when applied to T-3 uptake, it is believed that the results are related to the rate of T-3 uptake by the absorbent, the T-3 binding capacity of the proteins, and the rate at which these proteins dissociate with T-3. Since the rate of dissociation of T-3 from the protein is the rate determining step, such rate is the one primarily measured by the present method.

In practicing the present method any suitable absorbent may be used which under the conditions of the test absorb about 10-90 weight percent of the thyroid hormone in the test sample. Preferably the absorbent and the other test conditions are selected so that about 40-60 weight percent of the thyroid hormone from a serum sample of a euthyroid patient are absorbed. A preferred class of absorbents for use in the present invention are ion exchange resins. Anion exchange resins are particularly desirable where a radioactively labeled thyroid hormone is utilized for determining the percentage of uptake by the absorbent. The anion exchange resin serves to remove any radioactive breakdown products which might otherwise interfere with the test results. As will be seen in the examples hereinafter, a strong base anion exchange resin provides particularly desirable results.

Any technique for analytically measuring the percentage uptake of hormone by the absorbent is contemplated. A preferred procedure for accomplishing this is to include a preselected amount of radioactively labeled T-3

taining 8% by weight of cross-linkage, having a 100-200 mesh size, and in a column diameter of about 0.75 centimeters. Using such a column the residence time of the sample in the column is not more than about three mintes.

Preferably the fluid sample being tested will contain up to about 1 ml. of blood serum and preferably about .5 ml. of blood serum. Consistent with the prior art, the sample is conveniently diluted with a buffer solution preferably having a pH of about 5.

To illustrate the invention, the following procedure has been shown to give excellent results.

EXAMPLE

0.5 ml. of patient's serum is mixed with 2.5 mls. of 0.4 N sodium acetate buffer at pH 5 containing trace amount of radioactively labeled tri-iodothyronine. This mixture is allowed to sit for 20 minutes to insure random distribution of the radioactive T-3 between the serum and solution. This mixture is then passed over a strong base anion exchange resin in a column. The column contains 1.2 ml. of a strong base anion exchange resin in the chloride form of 8% cross-linkage and 100-200 mesh. The internal diameter of the column is about 0.75 cm. diameter. The effluent from the column is collected in a counting tube. The contents of the tube are then measured for the quantity of radioactivity. By comparison with a control such as normal pooled serum or commercial control serum of known value, an evaluation of the degree of unsaturation of the serum protein binding sites can be made.

The first line in Table I below indicates the results obtained with the materials described in the preceding paragraph. The data shown in lines 2-5 of the table were developed using the same procedure but different ion exchange resins and volumes as indicated.

TABLE I.—EFFECT OF RESIN TYPE ON PERFORMANCE

Resin	Resin volume, ml.	Flow rate, ml./min.	Control serum, percent eluted			TBI ¹
			Normal	Abnormal		
AG1X8, 100-200 mesh.....	1.2	1.0	43.4	30.0	.69	
AG1X4, 100-200 mesh.....	1.2	1.0	34.5	23.5	.68	
AG1X2, 100-200 mesh.....	1.2	1.0	36.0	24.4	.68	
AG50WX8, 100-200 mesh.....	2.0	.....	40.0	23.4	.59	
AG40WX2, 100-200 mesh.....	2.0	.....	36.7	24.4	.67	

¹ TBI=Thyroid Binding Index.

NOTE.—TBI value for abnormal serum was calculated to be .68 from charted results using the prior art batch method. AG Resins are ion exchange resins commercially available from Bio-Rad Laboratories, Richmond, California. AG1 Resins are strong base anion exchange resins. AG50W Resins are strongly acidic cation exchange resins. The number following the "X" indicates the weight percent of cross-linkage in the resin.

or T-4 in the serum sample. After equilibrium has been attained the sample is passed through the column and the amount of radioactively labeled T-3 or T-4 in the effluent is measured by conventional techniques. As understood in the art, the values obtained for uptake of the radioactively labeled hormone enable thyroid function to be evaluated by reference to values from known serum processed under comparable conditions. The desired information can be obtained by measuring the amount of radioactivity in the absorbent or in the column effluent. Preferably, the measurements are made on the effluent.

In achieving a retention by the absorbent of 10-90 weight percent of the hormone in the sample, a number of variables are involved. The absorbent, its type (i.e. whether or not it is an ion exchange resin including degree of cross-linkage if a resin), volume employed, and mesh size will affect the percentage retention. In addition, the column dimensions particularly its diameter will bear upon this result. In general, conditions are selected so that with the volume of sample fluid employed the desired extent of retention is achieved within the brief period of time noted. As will be seen in the example to follow, the desired thyroid hormone retention within a brief residence period can be attained using 1.2 ml. (particle volume) of a strong base anion exchange resin con-

What is claimed is:

1. A method for determining the uptake of thyroid hormone by a competitive binding absorbent therefor from a fluid sample containing thyroid hormone bound by thyroid hormone binding proteins comprising: disposing said absorbent in a column, flowing said fluid sample through and out of said column at a constant rate, said column dimensions and absorbent being selected to competitively bind and retain about 10-90 weight percent of the bound thyroid hormone in said fluid sample during a single passage therethrough, measuring the amount of thyroid hormone retained in said column relative to the amount present in the effluent therefrom, and evaluating the uptake of thyroid hormone from said sample by comparison with a control.
2. A method in accordance with claim 1 wherein said column dimensions, absorbent type, volume and mesh size, and the volume of said sample fluid are selected to provide a sample residence time of not more than about ten minutes.
3. A method in accordance with claim 1 wherein said absorbent is an ion exchange resin.
4. A method in accordance with claim 3 wherein said ion exchange resin is a cross-linked anion exchange resin.
5. An improved clinical procedure for evaluating thyroid status comprising: equilibrating a sample contain-

ing blood serum with a preselected amount of radioactively labeled thyroid hormone in a buffer diluent, providing a column of ion exchange resin adapted to absorb about 10-90 weight percent of the serum bound thyroid hormone in said sample, passing said equilibrated sample and diluent through said column at a constant rate, passage through the column being completed in not more than about five minutes, measuring the radioactivity of said column and/or the effluent therefrom, determining the percentage of thyroid hormone absorbed by said column and/or remaining in said effluent from said radioactivity measurement, and evaluating thyroid status of said sample by comparison with a control.

6. An improved method in accordance with claim 5 wherein said radioactively labeled thyroid hormone is 15 radioactively labeled tri-iodothyronine.

7. An improved method in accordance with claim 5 wherein said radioactively labeled thyroid hormone is 20 radioactively labeled thyroxine.

8. An improved method in accordance with claim 5 wherein said sample contains a buffer diluent.

9. An improved method in accordance with claim 5 wherein said ion exchange resin is a strong base anion exchange resin.

10. An improved method in accordance with claim 9 wherein said anion exchange resin contains about 8% 25 cross-linkage.

11. An improved method in accordance with claim 5 wherein said column of ion exchange resin is adapted to

absorb about 40-60 weight percent of thyroid hormone from a serum sample of a euthyroid patient.

12. An improved method in accordance with claim 10 wherein said ion exchange resin has a 100-200 mesh size, is present to provide a bed volume of about 1.2 ml. and a column diameter of about .75 centimeters and the residence time of the sample in the column is not more than about three minutes.

13. An improved method in accordance with claim 12 10 wherein said sample contains up to about 1 ml. of blood serum.

14. An improvement in accordance with claim 13 wherein said sample contains about .5 ml. of blood serum.
